ATTORNEY

UNITED STATES PATENT OFFICE.

GEORGE ALBERT DEIBLER, OF ELIZABETHVILLE, PENNSYLVANIA.

RAIL-CHAIR.

1,262,462.

Specification of Letters Patent.

Patented Apr. 9, 1918.

Application filed January 15, 1916. Serial No. 72,313.

To all whom it may concern:

Be it known that I, GEORGE ALBERT DEIBLER, a citizen of the United States, residing at Elizabethville, in the county of Dauphin 5 and State of Pennsylvania, have invented certain new and useful Improvements in Rail-Chairs, of which the following is a specification.

My present invention has relation to certain new and useful improvements in rail joints and chairs; and as its primary object it contemplates the provision of a novel device of this nature that may be quickly and easily associated with or removed from the 15 respective rails and which when in place will securely retain the same against lateral as well as longitudinal movement.

A further object of my invention is to provide a device of the type in question that 20 is extremely simple in construction, strong and durable and highly practical from both the standpoint of the manufacturer and the standpoint of the user; and which, it is believed can be manufactured at a comparatively low cost.

A still further object is to provide a single rail-web-brace of such rigidity and so constructed that the necessity for a second or opposite web-brace is obviated, thereby 30 greatly lessening both the cost of manufacture and the time and work required to replace and remove the same.

Various other objects and advantages will 35 become apparent during the continuance of the following description.

These objects are accomplished by such means as are shown in their preferred form in the accompanying drawings, described in the following specification and then more 40 specifically pointed out in the appended claims.

In the accompanying drawings wherein like characters designate like parts throughout the several views:—

45 Figure 1 is a view in top plan showing my invention as in its preferred embodiment and in conjunction with a pair of rails of conventional form; the rails being shown partly broken away and in section.

50 Fig. 2 is a cross sectional view taken on line 2—2 of Fig. 1.

In the drawings A designates a rail tie of the usual construction while B and C respectively designate a pair of rail members that are associated therewith and in

conjunction with which my invention is shown.

In reducing my invention to practice I first provide a base or bed plate 10 which may be constructed of metal, fiber or a like material and designed to be positioned beneath the respective end portions of the rails, as clearly shown in Fig. 2. A plate 11 is arranged longitudinally upon and adjacent one edge of the plate 10, as shown in Fig. 2, and a series of fastening members 12 are employed whereby a secure connection between the said plates may be attained. The plate 11 is in turn provided with an inwardly directed clamping lip or flange 13 which in use of my invention is designed to embrace the upper face of the base flange of the respective rails and has its inner end in abutting engagement with the web portions thereof.

I further provide plate 14 that is designed to be adjustably mounted adjacent the opposite edge of the base plate 10, by having adjustable bolts 15 pass through the lateral slots 16 thereof. The threaded end of each bolt 15 is made to seat in a suitable threaded aperture in the base plate 10 whereby upon proper rotation of the bolt, the head portion thereof may be brought into binding engagement with the plate 14 and the latter thus held in a rigid position. The plate 14 further carries, at its inner edge, an enlargement or head or brace element 17 which, in the use of my invention is designed to embrace the outer portion of the base flange of the rails, as at 18 and at the same time abut against the outer face of the web portion thereof, as clearly shown in Fig. 2. Consequently it will be noted that the enlargement 17 forms a dual function, namely, to further retain the rails against accidental lateral dislodgment and at the same time absorb the outward strain subjected on the rails, at their point of connection, caused generally by the passage of rolling stock in rounding curves.

In the present embodiment the web portion of the adjacent rails is provided with a series of spaced receiving apertures 19 which are designed to receive suitable lateral 105 nibs or studs 20 that are carried on the enlargement 17, as shown in Fig. 2. The nibs or studs 20 may be cast integral with or otherwise attached to the enlargement 17 whereby when positioned in the respective 110

apertures 19 of the rails, they will also tend to securely retain the latter against longitudinal movement.

Adjacent their free end, the nibs or studs 5 20 are provided with lateral key-ways 21 which, after the studs 20 are placed in position through the apertures 19, are designed to receive suitable locking keys 22; the latter in turn being split to form lips 23 whereby they may be locked in a secure position with respect to the nibs or studs, as clearly shown in Fig. 1.

The outer edges of the plate 10 as well as the outer edges of the respective plates 11 and 15 14 are provided with suitably spaced notches 24 to partially receive the shank portions 25, when the latter are driven into the tie, so that the spikes not only serve to retain the device against vertical and lateral movement but also securely retain the 20 same in longitudinal give.

The operation of my invention is substantially as follows:—

The rails B and C being positioned on the tie A in the usual manner are raised 25 slightly to permit the plate 10 to be slid thereunder and the lip 13 of the plate 11 made to engage the inner portion of the base flange thereof. After the plates 10 and 11 30 have been positioned in this manner, certain of the spikes 25 may be driven into the tie so as to retain said plates against movement in one direction, prior to the locking of the other plates in position. The plate 14 35 is now positioned on the plate 10, so that its enlargement 17 will lie upon the outer portion of the base flange of the rails, and subsequently moved laterally so as to bring the inner face of the enlargement into abut- 40 ting engagement with the outer wall of the web portion of the rails and position the nibs or studs 20 through the respective receiving apertures 19. When the plate 14 assumes this position, the bolts 15 may be 45 inserted and tightened so as to bring the head portion thereof into binding engagement with the plate 14 and thus lock the same against retrograde movement. The remaining ones of the spikes 25 may then 50 be driven into the tie so as to further lock the plates in a rigid position with respect to each other while the keys 22 may be subsequently positioned in the key ways 21 of the nibs or studs in the manner above set forth. 55 After the keys 22 have been positioned in place a chisel or other tool may be employed to bend the lip portions 23 thereof so that they will lock the same against dislodgment.

60 From the foregoing it is believed that the advantages and novel features of my invention will be readily understood and there-

fore further detail description is deemed unnecessary.

In reducing my invention to practice I 65 find that the form referred to herein as the most practical and preferred embodiment is the most efficient but realizing that certain conditions will necessarily vary in concurrence with the adoption of my device, I 70 desire to emphasize that fact that various minor changes in the details of construction and in the proportion of parts may be resorted to when required without sacrificing any of the advantages of my invention as 75 defined in the appended claims.

Having thus fully described my invention what I claim as new and desire to secure by Letters Patent is:—

1. The combination with the meeting ends 80 of two railroad rails and a plate supporting said meeting ends, of a combined rail-joint-connector and rail-web-brace consisting of a horizontal bar formed with a vertical surface adapted to fit against two meeting ends 85 of rail-webs and formed with a plurality of apertured studs adapted to extend through holes in said rail-webs, the apertures of said studs being spaced from said vertical surface a distance approximately equal to the 90 distance of the rail-webs, a plurality of keys each of which is seated in the aperture of a respective one of said studs and fitted snugly against the adjacent portion of the respective rail-webs, and means for securing 95 said bar to said plate.

2. The combination with the meeting ends 100 of two railroad rails and a plate supporting said meeting ends, of a combined rail-joint-connector and rail-web-brace consisting of a horizontal bar formed with a vertical surface adapted to fit against two meeting ends 105 of rail-webs and formed with a plurality of apertured studs adapted to extend through holes in said rail-webs, the apertures of said studs being spaced from said vertical surface a distance approximately equal to the 110 distance of the rail-webs, a plurality of keys each of which is seated in the aperture of a respective one of said studs and fitted snugly against the adjacent portion of the respective rail-webs, means for securing said bar to said plate, and a brace member secured to said plate and extending into contact 115 with the rail-webs at their respective bottom portions, so that the web contacting portion of said brace member is over-hung by the said keys.

In testimony whereof I affix my signature in presence of two witnesses.

GEORGE ALBERT DEIBLER.
